MARKING DEVICE

Samuel A. Hamnett, Los Angeles, Calif.

Application December 30, 1941, Serial No. 424,885

2 Claims. (Cl. 101—28)

This invention relates to a marking apparatus.

The general object of the invention is to provide an improved marking apparatus wherein movable type are employed and wherein novel means is provided for holding the type in the marker.

Another object of the invention is to provide a novel type holder for a marker device.

A further object of the invention is to provide a type holding member wherein a novel sliding sleeve holds the type holding member in position.

Other objects and advantages of the invention will be apparent from the following description taken in connection with the accompanying drawing wherein:

Fig. 1 is a top plan view of the marker body;

Fig. 2 is a section taken on line 2—2 of Fig. 1;

Fig. 3 is a top plan view of the jaw member;

Fig. 4 is a section taken on line 4—4, Fig. 3;

Fig. 5 is an end view on an enlarged scale showing the sleeve member;

Fig. 6 is a section taken on line 6—6, Fig. 5.

Fig. 7 is a section taken on line 7—7, Fig. 5.

Fig. 8 is a section taken on line 8—8, Fig. 5.

Fig. 9 is a perspective view showing the type member on an enlarged scale;

Fig. 10 is a perspective view with parts broken away showing the marking device;

Fig. 11 is a fragmentary, central sectional view, showing the device with the jaw closed;

Fig. 12 is a view similar to Fig. 11 showing the jaw open; and

Fig. 13 is a sectional detail showing the spring pressed type engaging member.

Referring to the drawing by reference characters, I have shown my invention as embodied in a marking device which is indicated generally at 10. As shown the device includes a body member 11 which includes a handle 12 and a type holding portion 13.

The portion 13 includes a recess 14 which has parallel side walls 15 and an end wall 16. At the inner end of the recess 14 I provide opposed arcuate grooves 17. In the end of the groove 17 I arrange a support member 18 the forward end edges of which are rounded as at 19 and are of a size so that they make a drive fit in the grooves 17.

Mounted within the recess 14 I show a jaw member 22 which has an upper surface 23 and a lower surface 24. The lower surface includes a bead 25 which pivotally fits in a groove 21 in the support member 18. The jaw member includes a tongue 26 which projects beyond the bead 25 and which is arranged in a recess 26 in

the body 13. The tongue 26 tapers upwardly as at 28 and thus projects above the plane of the body 13 as shown in Fig. 11. The jaw member includes a second bead 29 which is arranged to fit in a groove 30 in a type member 31. The type member may have a character 32 on the end thereof such as a number or a letter.

When the jaw member is in the position shown in Fig. 11, the bead 29 fits the groove 30 so that the type member is held in place. When the jaw member 22 is in the position shown in Fig. 12 the bead 29 is withdrawn from the groove 30 so that the type member 31 may be removed.

In order to provide means for operating the jaw member I provide a sleeve 33 which includes a top 34, a bottom 35 and ends 36. The top is provided with a slot 37 best shown in Fig. 7 and which includes a rear portion 38 and wider front portion 39. The portion 38 receives the tongue 26 on the jaw 22 when the sleeve is in advanced position. When the sleeve is in its rear position the tongue 26 enters the portion 39 of the slot. This front portion 39 has a bevelled face 40 which engages the tongue 26 and forces the inner end of the tongue downwardly thus rocking the jaw about the bead 25 to the position shown in Fig. 12.

In order to hold the sleeve in its forward position I provide the body 13 with a hole which includes a large upper portion 41, a reduced intermediate portion 42, a second intermediate further reduced portion 43, and an enlarged lower portion 44. The hole receives a pin member which includes a head 45 and a shank 46. The head 45 has a sliding fit in the hole portion 41 and the shank 46 has a sliding fit in the hole portion 43. A collar 47 engages the shank 46 and is disposed in the hole portion 44 and is secured to the shank to hold the parts assembled. A spring 48 surrounds the shank 46 and urges the head 45 upwardly where it is in the path of movement of the sleeve 33.

To move the sleeve the head portion 45 is depressed so that the sleeve may be moved rearwardly. As the sleeve member moves rearwardly the bevelled portion 40 engages the bevelled portion 28 of the tongue 26 on the jaw member and rocks the jaw member to the position shown in Fig. 12 in which position the type members 31 may be inserted or removed after which the sleeve is moved to its advanced position whereupon the head 45 of the pin member is urged outwardly by the spring 48 thus preventing accidental movement of the sleeve.

In order that all the type members may be

urged together I show type holding portion 13 as provided with an aperture 50 in which a ball 51 is arranged. The ball is urged inwardly by a relief spring 52 which is disposed in a slot 53 in the type holding portion.

From the foregoing description it will be apparent that I have invented a novel marking device which can be economically manufactured and which is sturdily constructed and is highly efficient for its intended purpose.

Having thus described my invention, I claim:

1. In a marking device, a body member including a handle portion and a type holding portion, the type holding portion having a recess adapted to receive a type member, a jaw member pivotally mounted upon said type holding portion, said jaw member having a rearwardly projecting tongue, said type holding portion having a second recess receiving said tongue, said tongue having a bevelled face, a sleeve slideable on said type holding portion, said sleeve having a groove re-

ceiving said jaw tongue, the wall of the sleeve defining said groove having a bevelled end adapted to depress the tongue when the sleeve is moved to one position and means to normally prevent rearward movement of the sleeve to said one position.

2. In a marking device, a body member including a handle portion and a type holding portion, the type holding portion having a recess, a jaw

10 member pivotally mounted in said recess, said jaw member having a rearwardly projecting tongue, said tongue having a bevelled face, a sleeve slideable on said type holding portion and engaging said jaw member, the inner wall of the sleeve having a bevelled portion adapted to engage the bevelled face on the tongue and depress the tongue when the sleeve is moved to one position and means to normally prevent movement of the sleeve to said one position.

SAMUEL A. HAMNETT.
